UNITED STATES PATENT OFFICE

168,363

ELECTRICALLY ILLUMINABLE DIAGNOSTIC SPECULUM

Hayes Martin, New York, N. Y., assignor to Welch
Allyn, Inc., Auburn, N. Y., a corporation of New
York

Application April 13, 1951, Serial No. 14,817

Term of patent 14 years

(Cl. D83—1)

To all whom it may concern:

Be it known that I, Hayes Martin, a citizen of the United States, residing at New York, in the county of New York and State of New York, have invented a new, original, and ornamental Design for an Electrically Illuminable Diagnostic Speculum, of which the following is a specification, reference being had to the accompanying drawing, forming a part hereof.

Fig. 1 is a view in side elevation of an electrically illuminable diagnostic speculum embodying my new design;

Fig. 2 is a top plan view of the speculum shown in Fig. 1;

Fig. 3 is a slightly reduced bottom plan view thereof;

Fig. 4 is a slightly reduced view in elevation of the side of the speculum opposite that shown in Fig. 1;

Fig. 5 is an end elevation of the speculum taken from the left of Fig. 1; and

Fig. 6 is an end elevation of the speculum taken from the right of Fig. 1.

The speculum handle is shown in broken lines in Figures 1 and 3 for illustrative purposes only.

I claim:

The ornamental design for an electrically illuminable diagnostic speculum, substantially as shown and described.

HAYES MARTIN.
